UNITED STATES PATENT OFFICE

148,622

DESIGN FOR AN ESCUTCHEON FOR DOOR-BELL PUSH BUTTONS

Pauline Hillman, Hillside, N. J.

Application October 21, 1946, Serial No. 134,145

Term of patent 14 years

(Cl. D26—13)

To all whom it may concern:

Be it known that I, Pauline Hillman, a citizen of the United States, residing at Hillside, in the county of Union and State of New Jersey, have invented a new, original, and ornamental Design for Escutcheon for Doorbell Push Buttons, of which the following is a specification, reference being had to the accompanying drawings, forming a part thereof.

Figure 1 is a plan view of the escutcheon for doorbell push buttons, showing my new design.

Figure 2 is a side elevation of the same.

I claim:

The ornamental design for an escutcheon for doorbell push buttons, as shown.

PAULINE HILLMAN.
